[57] **CLAIM**

The ornamental design for wall lamp, as shown and described.

DESCRIPTION

FIG. 1 is a top, front perspective view of a wall lamp showing my new design;

FIG. 2 is a right hand side elevational view thereon on an enlarged scale;

FIG. 3 is a left hand side elevational view thereof on an enlarged scale;

FIG. 4 is a top plan view thereof on an enlarged scale;

FIG. 5 is a bottom plan view thereof on an enlarged scale;

FIG. 6 is a front elevational view thereof on an enlarged scale;

FIG. 7 is a rear elevational view thereof on an enlarged scale.

The perforations in the two sections of the diffuser are partially shown for convenience of illustration, it being understood that the perforations are continuous over the surfaces on which they are shown.

FIG. 1

FIG. 2
